(57) **CLAIM**

The ornamental design for a connector block for a garden bed, as shown and described.

DESCRIPTION

FIG. 1 is a front perspective view of a connector block for a garden bed;

FIG. 2 is a right side view of the connector block for a garden bed, the left side view being a mirror image thereof;

FIG. 3 is a top view of the connector block for a garden bed;

and,

FIG. 4 is a bottom view of the connector block for a garden bed.

The broken lines shown in FIGS. 1–4 illustrate portions of the connector block for a garden bed that form no part of the claimed design.
